[57] ABSTRACT

In a fluid supply system of the type having an electric motor actuating either a pump or a valve controlling the flow of fluid, there is provided a flexible conduit portion cooperating with a preloaded lever, which at occurrence of a pressure-alteration, brought about at the opening of one or more draw-off valves in the system, will energize the motor to actuate said pump or valve. Hereby the manual activity at drawing off fluid is considerably reduced and the operating time for the motor can be kept substantially to correspond to the time for drawing off.

FIG. 7

FIG. 8

FIG. 9

FIG. 10

DEVICE FOR FLUID SUPPLY

BACKGROUND OF THE INVENTION

The present invention refers to a device for fluid supply, comprising a pump or a stop valve being connected in a supply conduit and actuated by a motor.

The device is particularly advantageous at fluid supply systems of temporary or mobil nature and an example of a convenient fitting is the water supply system of a caravan. The use of the device is however not limited to this field, but the device may be fitted in most types of fluid supply systems.

SUMMARY OF THE INVENTION

The purpose of the invention is to provide a device by aid of which the manual activity at drawing fluid out off the system is reduced to a minimum at the same time as the operating time for the motor is reduced substantially to exact correspondance to the time for drawing off. The device according to the invention is mainly characterized thereby that the pump or the stop valve connected in the supply conduit is adapted to be shifted due to a dislocation of a springy member pressing against a flexible portion of the conduit, which springy member is adapted to switch on and off a power supply circuit to the motor actuating the pump or the stop valve resp., said dislocation being effected by shifting a draw-off valve connected in the conduit.

BRIEF DESCRIPTION OF THE DRAWINGS

FIGS. 1 and 2 show in schematic connection systems the device according to the invention in closed and open positions resp.

FIGS. 3 and 4 show a modification of the device according to the invention in positions corresponding to FIGS. 1 and 2 resp.

FIG. 5 is a third embodiment of the invention in closed position.

FIG. 6 illustrates a further embodiment according to the invention in closed position.

FIGS. 7 and 8 show in closed and open positions resp. a detail from the device according to FIGS. 1 and 2, and

FIGS. 9 and 10 illustrate schematically in corresponding views corresponding details of the embodiments according to FIGS. 3 to 6.

DESCRIPTION OF THE PREFERRED EMBODIMENTS

In FIGS. 1 and 2 a supply conduit 1 is provided with a pump 3, which is actuated by a motor 2. The supply conduit 1 is along one section, or along its entire extension, designed as a flexible portion 4, preferably a hose. Against the flexible portion 4 of the supply conduit engages a springy member 5, which has such a preload that the member at rest compresses the flexible conduit portion 4 so much that fluid passage beyond this point is impossible. The member 5 is provided with a part 6 intended for external, preferably manual actuation, whereby the member may be brought to move so much away from the conduit that this due to its self-flexibility will open entirely and allow maximum fluid passage. The springy member 5 thus in this embodiment acts as a draw-off valve and its side turned away from the flexible conduit portion 4 is adapted, at the opening of the conduit, simultaneously to act on a switch 7 to close an electric circuit 8 energizing the motor 2. The motor 2

thus starts at the same time as the flexible portion 4 of the supply conduit 1 is opened, and the pump 3 driven by the motor hereby delivers fluid to a draw-off position 9. As soon as the external pressure on part 6 of member 5 ceases the fluid passage through the conduit is cut off, due to the fact that the member 5, compresses the flexible portion 4 of the conduit, and simultaneously is the power supply to the motor 2 disconnected whereby the pump 3 stops.

10 The constructional design of the device at the embodiment according to FIGS. 3 and 4 corresponds mainly to that of FIGS. 1 and 2. The springy member 5 is however not designed as a draw-off valve, but the draw-off position 9 in this embodiment is provided with 15 a draw-off valve 10 of conventional design. As can be seen in FIG. 3 it is also possible to connect several draw-off positions 9 to the same conduit. In this case the springy member 5 has no part for external actuation, but the member is instead preloaded sufficiently to deform the surface of the flexible conduit portion 4 somewhat, when one or more of the draw-off valves 10 are opened and fluid is allowed freely to flow through the system. The switch 7 cooperating with the member 5 in this position closes the power supply circuit 8 for 20 the pump motor 2, whereby the pump 3 starts the transport of fluid through the system. When all the draw-off valves 10 again are shut, the pump during a short period of time will continue to deliver fluid into the system. The pressure in the conduit 1 hereby is increased 25 and the flexible portion 4 resumes its normal form against the action of member 5. The member 5 hereby is brought to act upon the switch 7 in such a manner that this breaks the circuit 8, whereby the motor 2 and thereby also the pump 3 is stopped. When one or more of the draw-off valves 10 the next time are opened the pressure in the conduit portion 4 will be reduced so 30 much that the member 5 again causes the slight deformation of the conduit wall, whereby the circuit 8 again is closed and the fluid delivery is resumed.

35 The system according to FIG. 5 differs from that shown in FIGS. 3 and 4 thereby that the pump is replaced by a shutoff valve 11 being connected in the supply conduit and actuated by the motor 2. The supply conduit is in turn fed from a reservoir 12, which is under pressure. The mode of operation at this embodiment is analogue with that described in FIGS. 3 and 4, whereby the motor 2 instead of starting and stopping a pump, due to the dislocations of the member 5, opens 40 resp. closes the valve 11, which delivers fluid into the system.

45 In FIG. 6 there is shown a further modified device according to the invention. The main parts of the device correspond entirely to the design shown in FIGS. 3 and 4. At the draw-off position 9 the manually adjustable draw-off valve 10, however has been replaced by a two-way valve 13, which controls the passage to the draw-off position 9 in dependence of for instance a level indicator 14 in a tank 15 to which the fluid is delivered. In 50 this way there is provided a simple self-actuating fluid supply system.

55 In FIGS. 7 and 8 there is illustrated a detail in a schematic, partly cut side elevation of the embodiment according to FIGS. 1 and 2. From the figures the design of member 5 can be seen and the member comprises a loop of a resilient material, e.g. spring steel, which loop is enclosed in a housing 16, which acts as a holder-on 60 for the member and at the same time protects the

switch 7 against contaminations and external damage. When the external part 6 of the member, as shown in FIG. 7 is unactuated the member 5 is pressed by its own preload so hard against the upper portion of the housing 16, that the flexible portion 4 of the conduit, which is located therebetween, is compressed in such a high degree that fluid may not pass therethrough. The side of the member 5 turned away from the portion 4 in this position is located so far away from a contact tongue being part of the switch 7 that this due to its own flexibility maintains the electric circuit, being part of the device, in a non-conducting position. When fluid delivery is wanted the external part 6 of the member 5 is pressed downwards as shown in FIG. 8 whereby the portion of the member 5 engaging the flexible conduit portion 4 is removed so much from the conduit that this due to its own flexibility is opened. As the springy member 5 so is exerted to a dislocation, its side turned away from the conduit will press down the contact tongue against the contactor cooperating therewith and the power supply circuit is closed and the fluid delivery is started.

FIGS. 9 and 10 show in elevations corresponding to FIGS. 7 and 8 corresponding details at embodiments according to FIGS. 3-6. The flexible conduit portion 4 in FIG. 9 — when the draw-off position is blocked — is exerted to such a high internal pressure that the member 5, which is designed as a flexing tongue and is connected in the housing 16, may not deform the wall of the conduit. Hereby the end of the member 5, which is designed as a part of the switch 7, is located at a distance from its cooperating contactor, whereby the electric circuit 8 energizing the motor 2 is in non-conducting state. When the pressure in the flexible portion 4 of the conduit is reduced, due to the fact that the draw-off device is opened, the member 5 due to its preload can deform the conduit somewhat, whereby the member makes a short movement, which is sufficient to close the switch 7 to the electric circuit 8 of the motor 2, whereby fluid delivery is started and continues

until the draw-off device again is shut. By means of the thus described device there is provided a simple and reliable system for fluid supply, and the invention is of course not limited to the modifications in the described embodiments but the device may be modified in several ways within the scope of following claims.

What I claim is:

1. A device for fluid supply comprising a pump or a stop valve being connected in a supply conduit and actuated by a motor, wherein the pump or the stop valve connected in the supply conduit is adapted to be shifted due to a dislocation of a springy member pressing against a flexible portion of the conduit, which springy member is adapted to switch on and off a power supply circuit of the motor actuating the pump or the stop valve resp., said dislocation being effected by shifting a draw-off valve connected in the conduit.
2. A device according to claim 1, in which the member pressing against the flexible portion of the conduit is preloaded and designed at rest to compress the conduit so much that the fluid passage is blocked, the member being designed as a draw-off valve, which is adapted due to external actuation to be removed from the conduit so much that this due to its self-flexibility again will open, and that the member is adapted during its dislocation to actuate a switch in the power supply circuit of the motor.

3. A device according to claim 1, in which the member engaging the flexible conduit is actuated by the fluid pressure prevailing in the conduit and that the spring pressure by which the member acts on the conduit is so chosen that the cross-sectional area of the conduit is only slightly reduced when fluid is drawn off, said member being designed to actuate a switch in the power supply circuit of the motor by its dislocation due to alternations in the pressure in the flexible portion of the conduit when the position of the draw-off valve is shifted.
